LOCK

Horace A. Daum, Seattle, Wash.

Application November 16, 1937, Serial No. 174,787

4 Claims. (Cl. 70—146)

This invention relates to improvements in door locks, and more particularly to locks designed to be used on large doors where it is desirable to lock, latch, or secure the doors at a plurality of points by means distributed to share the forces thereon and wherein all holding means are operated simultaneously by means of a handle or knob common to all. Also, the invention relates to such locks for doors of smaller sizes where great holding strength is desirable.

It frequently is necessary, or desirable, with doors of large size, or area, to provide more than one locking point and to provide that it may be released at all points simultaneously in order to simplify the opening thereof. Large doors of the kind used in pairs, have a tendency to warp inwardly at the center, and this is usually enough that the latching bolt of the lock carried on one door will pass by the other door and catch on the inner edge thereof, or on large single doors the latch passes by the door frame in the same manner. This results in a strain on the door, which is damaging and which, if continued over a period of time, will necessitate repair or complete replacement. Furthermore, this is disagreeable to the person closing the door.

The present invention has for an object to provide improvements whereby these undesirable results are eliminated, and therefore one of the novel features of the invention is the provision of means for preventing the latching bolt from slipping out of or past the recess that receives the locking bolt except as is provided for.

Also, an object of this invention is to provide a latch or lock to be located at the center of the swinging edge of the door, as is the usual practise, and also latches or locks located at the top and bottom thereof, operated by rods connected to the main locking units and operated by one opening knob or handle; the latching bolt of the main locking unit, or all of the locking units, designed to receive in slots therein specially designed retaining plates.

Further objects of the invention reside in the details of construction of the parts in their combination and mode of operation, as will be hereinafter fully described.

In accomplishing the above stated and other objects of the invention, I have provided the improved details of construction, the preferred forms of which are illustrated in the accompanying drawings, wherein—

Fig. 1 is an inside elevation, partly broken away, of a pair of large doors, such as used on

garages or buildings, equipped with locks in accordance with the present invention.

Fig. 2 is a horizontal section on the line 2—2 in Fig. 1.

Fig. 3 is an enlarged horizontal section, on the line 3—3 in Fig. 1, particularly illustrating the latching bolt and the retaining plates engaging within the latching recess.

Fig. 4 is a vertical section on line 4—4 in Fig. 3.

Fig. 5 is a vertical section on the line 5—5 in Fig. 4.

Fig. 6 is a detail of certain operating parts of the lock.

Fig. 6a is a detail of the lock mechanism.

Fig. 7 is a vertical section on the line 7—7 in Fig. 3.

Fig. 8 is a vertical section on the line 8—8 in Fig. 7.

Fig. 9 is a cross section on the line 9—9 in Fig. 1.

Fig. 10 is a cross section on the line 10—10 in Fig. 9.

Fig. 11 is a view illustrating the use of a latch or lock of a modified form suitable where one door is used.

Fig. 12 is an enlarged detail of the modified latch.

Fig. 13 is a cross section on the line 13—13 in Fig. 12.

Fig. 14 is a side view of an alternate form of construction.

Fig. 15 is a front view of the same.

Fig. 16 is a back view of the same.

Referring more in detail to the drawings—

The reference numerals 10 and 11 designate, respectively, the two swinging doors of a garage or building, hinged respectively at 10' and 11', and adapted to swing outwardly from the enclosure as indicated by the direction of the arrows in Fig. 2. What will be referred to as the main locking unit and the receiving latch unit are designated, respectively, at 13 and 14. These units would ordinarily be located within reach, preferably at points somewhat below the center of the door and at the swinging edge thereof.

Located at the upper and lower corners of the doors, respectively, and at the swinging edges, and directly in line with the main locks 13 and 14 are corner latches 15—15' and 16—16'. These corner latches 15—15' are adapted to catch and hold in recesses in the receiving housings 17—17' at the top of the door, and the lower corner latches, as here shown, are adapted to likewise catch and hold in reinforced recesses 18—18' in a concrete floor 19. Rods 20 connect the bolts of

the corner latches with the actuating means of the main locking units 13 and 14 in such a way that upon the operation of the latter, by their handles 21 and 22, as presently described, the 5 corner latches, as well as the main lock, will be released so as to permit the opening of the doors.

Referring to Figs. 3 to 8 inclusive, it will be seen that the housing of the lock unit 13 comprises a metal back plate 25, flanged along one edge, as at 25a, to overlie the edge of the door 11 in which it is mounted, and a formed cover 26 is affixed to and overlies the plate 25, forming a housing which contains the mechanism of the 15 lock. Likewise, the housing of the lock unit 14 comprises a metal back plate 28 flanged as at 28a, to overlie the edge of the door 10, in which it is mounted, and a formed cover 29 is affixed thereto and provides a housing which contains the mechanism of the lock, as will presently be described.

Handles 21 for lock unit 13 are provided at the inside and the outside of the door. One handle member has an integral mounting shank 21a, square in cross section, which extends through the lock and also through a bearing plate 31' fixed to the outer handle as seen in Fig. 5, and which plate 31' is retained by an overlapping plate 31''. The shank, at the outside of the door, extends into a square socket 21' in the outer 30 handle and is secured therein by a set screw 21x. The square shank 21a extends through a square hole 30a in the barrel 30 that is centrally formed in the lock operating lever 31, which, as seen in dotted outline in Fig. 4, normally lies in a horizontal position. The barrel 30 is rotatably mounted in the lock housing and the lever, at its opposite ends, mounts a pair of rollers 31a which, at their top edges, are in rolling contact with a horizontal shoulder 32a of sliding cam plate 32, 35 referred to as the outer plate, and at their bottom edges are in rolling contact with a shoulder 34a of a sliding cam plate 34, referred to as the inner plate; these plates being vertically slidable in the lock housing under the turning action 40 of the handles. The relationship of these cam plates is best shown in Figs. 4 and 5, and it will be observed that they have openings therethrough for passage of the handles.

A latch bolt 35, of substantially square 50 cross section and rounded at its outer end, as at 35a, is held in a guide housing 36, which is affixed horizontally to the main back plate 25 of the lock. A spiral spring 37 set in a socket in the door and fixedly mounted at one end and 55 having its opposite end secured to the bolt operates to hold the latch tongue 35 yielding on its extended position and yields to allow the bolt or tongue to be retracted.

Extending from the latch tongue, or bolt, 35 60 into operative contact with cam surfaces of the vertically slidable plates 32 and 34, is a bolt actuating stud 38. It will be understood by reference to Figs. 4 and 5, that the inner plate 34 has a triangular opening with an inclined cam edge 65 34b, and that the overlying portion of the plate 32 has a triangular opening with an inclined cam edge 32b. These two openings overlap, as shown in Fig. 4. On turning the lock handle, in either direction, the plates are caused to move vertically; plate 32 being actuated upwardly, and plate 34 downwardly. This sliding action of the plates causes the inclined cam surfaces 32b and 34b to act on stud 38 to move the bolt 35 inwardly and thus to release or unlock the door. 70 When the handle is released, the spring acting

on the bolt moves it back to extended position and the pressure of the stud against the cam surfaces causes the plates to be moved back to normal positions.

At its upper end, the plate 32 has an outwardly 5 formed portion 40 in sliding contact with the cover plate 26 and this operates to take side thrust and to hold the upper end of the plate in proper alinement. This outward bend of the upper part of the plate prevents its interference 10 with the rod 28. It also provides clearance for the rod 28, which is affixed to the upper end of plate 34, and extends through a hole 42 in the cover plate 26 to the latch device at the upper edge of the door. Elongated openings 43 and 44 15 in the cam plates 32 and 34 respectively, provide for the passage of the handles 21 and permit the plates to be moved up and down inside of the housing.

A locking arrangement comprising a rotary 20 spindle 45 extends through the lock housing, as in Fig. 5, and is revoluble in openings provided in the plate 25 and cover 26; the spindle having cylindrical bearing portions 45a and 45b. Between the bearing portions, the spindle is rectangular in cross section, as shown in Fig. 4, and this part is normally contained within circular openings 46 and 47 in the sliding cam plates 32 and 34 respectively, and in direct alinement with slots 46a and 47a, that extend downwardly and upwardly respectively from these holes 46 and 47. A turning handle 48 is affixed to the end of the spindle at the inside of the door and provides a manual means whereby the spindle may be turned 30 so as to throw the rectangular portions of the spindle to horizontal position, crosswise to the direction of the slots 46a-47a, thereby to prevent movement of the cam plates and the movement of the latches.

A key barrel 50 is mounted in the outside face 40 of the door, in the usual way, and, as shown in Fig. 6a, a gear 51 is revolvably mounted on the inside face plate 25 of the lock, and provided with a square opening to receive the square bolt 51a connected with the lock tumbler. Gear 51 may 45 mesh with a gear segment 52 revolvably mounted on the face plate of the lock. A key may be applied to the lock barrel 50 to turn the bolt 51a therein, thus to rotate gear 51 into mesh with gear segment 52, and incidentally to rotate rectangular part 45 between locking and unlocking position. As shown in Fig. 6a, there is a spring 50 pressed latch 53 engaging a notch 52b in segment 52, to yieldingly hold the bolt in unlocked position. A similar notch 52a is provided to receive 55 the latch 53 to hold the bolt in locked position.

Contained within the housing of the lock unit 14, which comprises the back plate 28, and the cover plate 29, is the lock operating lever 55, mounted by handles 22 like those of the unit 13. 60 The operating lever 55 lies in a horizontal position and mounts a pair of rollers 55a at each end thereof, which engage at their top surfaces against a shoulder 56a formed on a sliding plate 56, and on the bottom surfaces abut against a 65 shoulder 57a formed on a sliding plate 57. The connecting rods 26 are affixed to the sliding plates 56 and 57, and the compression springs 59 hold the plates yieldably in normal position, as shown in Figs. 7 and 8.

A strengthening plate 85, mounted on the rearward side of the back plate 28, and conforming to the shape thereof, is equipped with a pair of spaced, vertically alined studs 86 which are internally threaded to receive bolts 87 which pivot- 70

ally mount thereon latch tongue retaining plates 88, as seen in Figs. 3 and 4. These latch plates have ends disposed to be received, upon the closing of the doors, in slots 89 formed longitudinally in the top and bottom edges of the tongue 35. An extension spring 90, attached at its ends to pins 91 in the plates, draws these plates yieldably together. This spring is supplemented by other springs 90' mounted on the studs 86 and 87.

It may be stated that a tumbler lock 50 corresponding to that in unit 13, may also be incorporated in the lock unit 14, as shown in dotted lines in Figs. 7 and 8.

Figs. 9 and 10 are enlarged, sectional details of the latches 15 and 16, each of which consists of a back plate 60 and a cover housing 61, joined together. The latch bolt 63 is slidable therein and a compression spring 62 contained within the housing holds the latch bolt 63 at its extreme extended position. A rod 64 is threaded into the latch tongue 63, and extends through an opening 65 in the end wall of the housing 61. An enlarged portion, or flange, 66, on the outer end of the rod 64, abuts against the end wall of housing 61 and limits the distance to which the latching bolt extends beyond the opposite end of the housing. A rivet or stud 68, in the housing wall, spaced somewhat back from the inner end of the latch bolt 63, acts as a stop to limit the extent to which the bolt may be retracted. The connecting rod 20 is attached within the slotted outer end of the rod 64 by means of a pin 70.

On rotation of a handle of unit 13, the sliding plate 32 will be moved in an upward direction and the sliding plate 34 will be moved in a downward direction. Consequent to this, the stud 38 extending from the latch bolt 35, is forced laterally by the action of the cam surfaces 32b and 34b, in this way retracting the latch bolt 35, compressing the spring 37.

Also, upon the motion of the sliding plates, the rods 20 are moved so as to retract the latch bolts 63 of the latches 15 and 16. This allows the door 11 to open.

In Fig. 11, I have illustrated a variation of construction of the latch 15, to be used upon single doors where it is desirable to latch horizontally to the side wall, instead of vertically to the portion directly above the door. This latch is designated by the reference numeral 75, and has a receiving recess 75a to receive the latch bolt.

In Figs. 12 and 13, I have shown enlarged sectional details of the latter type of latch, and it consists of a base plate 76 with a formed housing 77 which contains the latch bolt 78. A spring 79 yieldably holds the latch tongue in its forward or extended position. A cam plate 80 operates to withdraw or retract the latch bolt 78.

The cam plate 80 lies between the back plate 76 and the latch bolt 78 in a guideway 81, formed by a cut out section in the housing flange 77a. The cam plate 80 has an angular surface 83 arranged to act on a roller 83a fixed to the latch bolt so that incident to a motion in a downward direction of the cam plate, the latch tongue will be operated inwardly to its retracted position.

Assuming the device to be so constructed, and assuming the doors to be closed, they would be opened in the following manner: The handles 21 and 22 are turned either upwardly or downwardly, thus rotating the operating levers 31 and 55, to actuate the sliding plates 32 and 34 in the lock 13, and the sliding plates 56 and 57 in unit 14.

In closing the doors, the rounded outer end of the bolt 35 will engage the formed portion 28a of the back plate 28, as seen in Fig. 3, and cause the bolt to be moved inwardly against the action of spring 37. This allows the door 11 to close to the point where the latch tongue comes into alignment with its receiving and retaining slot, and then it enters therein, holding the doors together in a closed position. The outer ends of the retaining plates 88, when engaged by the rounded end of the bolt, are forced apart, then snap into the bolt slots 89, thus to operate to hold the latch tongue 35 from being again forced inwardly by reason of its rounded nose portion 35a engaging the lock housing and slipping out of the opening to the inner edge of the door as is frequently the case in very large doors.

At the same time that the bolt 35 snaps into place, the corner latches 15-15' and 16-16' snap to a locked position in their respective recesses 17-17' and 18-18'.

The lock 14 operates in the same manner to release the latch bolts 63 in the latches 15' and 16' from their recesses 17' and 18', by the rollers 55a operating against the shoulders 56a and 57a of the sliding plates 56 and 57, against the compression springs 59. The upward motion of the plate 56 and the downward motion of plate 57 operates the rods 20.

Upon release of the handles 22, the springs 59 bearing against the shoulders 56a and 57a of the sliding plates 56 and 57 in the lock unit 14 bring the operating lever 55 back to a horizontal position, and also the handle 22. Also upon the release of the handles 21, the spring 37 bearing against the latch bolt 35 forces the sliding cam plates to the position holding the operating lever 30 in a horizontal position by the stud 38 bearing against the cam surfaces 32b and 34b.

With the locking block 45 in a vertical position, as shown in Fig. 4, it permits the sliding plates 32 and 34 to move upwardly and downwardly by reason of the slots 46a and 47a. By turning the locking block 45 to a horizontal position in the circular openings 46 and 47, it is no longer disposed to allow the slots 46a and 47a to slide past it and in this way holds the sliding plates 32 and 34 against movement and holds the entire latch locked.

This may be accomplished by the lever 48 from the inside, or through a key in the tumbler lock 50 through one revolution, and the gears 51 and 52, into mesh as seen in Fig. 6.

As illustrated in Figs. 14, 15 and 16, I have provided the latching unit 100, which is a latch bolt 55 receiving mechanism. This consists of a back plate 101 and solidly joined top plates 102 and 102b, held spaced from the back plate by sleeves 103 on connecting bolts 104. The plates 102 and 102b are so located as to leave an opening 105 for the latch bolt 106 to be received in. Two latch bolt holders 107 and 108 are disposed to slide in the channel formed by the cross members 109 and 110, and be held in a closed position by the springs 111.

Pivotedly mounted by the studs 115 are two opening levers 116, which are urged by the springs 118, which has one end affixed to the back plate 101 and the other end affixed to the opening lever, to a closed position, abutting against the stops 120. Rollers 116' are mounted at the swinging ends of levers 116.

A link 121 is connected within a slot 122 in the opening lever 116, and to a stud 123 which extends from the tongue holders 107 and 108. A slot 125

in the cross members 109 allows the stud 123 to move in an outward direction, and a slot 126 in the cross member 110 allows for movement of the spring 111 subsequent to the outward opening 5 movement of the bolt holders 107 and 108. A sliding plate 128 is yieldably mounted by the spring 111, in such a way that it abuts against the cross members 110 and against the latch bolt holders 107 and 108, and is moved rearwardly 10 upon the entering of the latch bolt 106.

Assuming the device to be so constructed, its operation will be as follows: It is intended that this latch bolt receiving mechanism be used with the conventional door latch or lock without the 15 customary cam surfaces, and that by retracting the latch bolt in the usual manner opens the door. In closing the door, the latch bolt 106 is brought to bear against the opening lever 116 which swings inwardly against the tension of 20 the springs 118 as the door is closed and the latch bolt is moved inwardly. The latch tongue holders 107 and 108 are opened apart by the operation of the opening levers 116 and the links 121. As soon as the latch bolt has passed the operating 25 levers, they spring to a closed position, as illustrated in Fig. 14, by reason of the spring 118, and then when it has passed the bolt holders 107 and 108, they in turn spring to a closed position by reason of the springs 111. It should be understood, however, that the plate 128 is moved back 30 by the latch bolt. Should the door fail to be closed sufficiently to catch the latch bolt behind the bolt holders 107 and 108, it will be held by the shoulders 116a of the opening levers 116. 35 This provides a double catch latch, and is intended to be used upon latches wherein a very heavy spring is utilized in the latch bolt unit, so that the door may be closed easily, but greater effort must be exerted to open it; such locks being especially adapted to use in automobile doors. 40

Having thus described my invention, what I claim as new therein and desire to secure by Letters Patent is:

1. In a lock for a door adapted to swing between 45 open and closed position, a door locking means comprising locking bolts mounted by the door at top and bottom edges, a lock housing mounted on the door at a location between the said edges, a pair of slide plates contained within the housing 50 in the opposite end portions thereof, rods operatively connecting the plates respectively with the bolts; said plates having adjacent end portions overlapped and formed with turned opposedly related parallel flanges, a handle mounted 55 in the housing and having a rotatable shaft extended between the plate flanges, and a cam lever fixed on the shaft engageable with the flanges for a simultaneous shifting of the plates in opposite directions to effect an unlocking action of the bolts; each of said plates having a slot formed 60

therein in the direction of its movement and having an enlargement in the slot and a locking spindle mounted in the housing extending through said slots, and normally permitting movement of the plates and adapted to be turned while in the 5 enlarged portions of the slots to effect locking engagement with the plates.

2. In a lock for a door adapted to swing between open and closed position, a door locking means comprising locking bolts slidably mounted on the 10 door at top and lower edges thereof, means yieldingly urging the bolts to locking positions, a lock housing fixed on the door at a location between the bolts, a locking bolt slidably mounted in the housing and extending therefrom, a pair of slide plates 15 in the housing, rods connecting the plates respectively with the locking bolts at top and lower edges of the door; said slide plates having edge portions in overlapped relation and formed with flanges in opposed relation, and each of 20 said plates having an opening forming a cam surface, a stud on the locking bolt of the housing engaged by said cam surfaces, a handle for the lock having a shaft revolvably mounted by the housing and extended between the plate flanges, 25 a lever fixed on the shaft with ends extended at opposite sides thereof to engage said flanges whereby to simultaneously actuate the plates to effect a simultaneous retraction of all the bolts.

3. In a door lock for a door adapted to swing 30 between open and closed positions, a housing fixed to the door, a latch bolt slidably therein with one end extending beyond the door edge, yieldable means urging the bolt to its extended position, a keeper adapted to receive the end of the latch 35 bolt on closing the door by causing the bolt to be depressed into the housing; said bolt having a rounded end and slots parallel therewith in its opposite sides, a pair of retaining plates pivotally mounted in the keeper, a spring urging said plates together; said plates having camming edges to be engaged by the latch bolt end to spread them 40 apart for seating in the slots on entrance of the bolt into the keeper.

4. In a lock for a door adapted to swing between 45 open and closed position, a lock housing, a lock bolt slidably mounted in the housing and extending therefrom and means for yieldingly urging it into extended position, and a pair of 50 pivotally mounted retaining plates adapted to be engaged by the extended end of the bolt, and to be spread apart thereby and a spring joining the plates and causing them to lock with the extended lock bolt, wherein the said lock bolt has a rounded end portion provided on opposite sides 55 with slots, and wherein the retaining plates are adapted to be spread apart by the rounded end of the bolt acting thereon and to be seated in the said slots.

HORACE A. DAUM. 60
